UNITED STATES PATENT OFFICE.

ERNEST HUNOLD, OF PROVIDENCE, RHODE ISLAND.

SCISSORS AND SHEARS.

No. 880,535.

Specification of Letters Patent.

Patented March 3, 1908.

Application filed February 15, 1907. Serial No. 367,513.

To all whom it may concern:

Be it known that I, ERNEST HUNOLD, a citizen of the United States, residing at Providence, in the county of Providence and State 5 of Rhode Island, have invented certain new and useful Improvements in Scissors and Shears, of which the following is a specification, reference being had therein to the accompanying drawing.

10 My invention relates to scissors and shears of all kinds, and has for its primary objects a means for lubricating the shear members at and adjacent to their pivotal points, to prevent excessive wear and binding of the parts, 15 and means for cushioning the pivoted members.

The invention consists in introducing an absorbent material within the inner face of one of the pivoted members.

20 It further consists in using as the absorbent a compressible material which will contact with the surface of the adjacent pivoted member.

In the drawings which constitute a part of 25 these specifications Figure 1 is a top plan view of a pair of scissors or shears embodying my invention. Fig. 2, a rear elevation of the same, and Fig. 3, a section of the same on line $x x$ of Fig. 2.

30 Like reference characters indicate like parts throughout the views.

A and B represent the usual shear members, comprising respectively the blade portions, a and b ; the body portions, a' and b' ; 35 and the finger loops or handles, a'' and b'' .

C is the connecting screw or other usual pivotal member.

The inner face of the body, b' , of the shear member at a point between the screw and the 40 handle has a circular cavity or seat, D, extending from whose base to the opposite face of the shear member, B, is an air passage, d , of less diameter than that of the cavity, D. In the cavity is placed a compressible absorbent material, either fabric or fiber, but 45 preferably felt, E, which rests upon the base of the cavity, and whose outer portion contacts with the inner face of the body portion, a' , of the shear member, A. The material, E, 50 is saturated with oil, whereby the contacting surfaces of the shear members and the pivot members are supplied with a sufficient, but not excessive, supply of lubricant for an indefinite period. The constant oil supply prevents 55 the usual binding and wear of the body portions of the shear members. The felt or

fiber, E, being compressible exerts a slight pressure upon the face of the shear member, A, thereby cushioning the parts, facilitating their coöperation, and protecting them from 60 derangement by violent blows or jars when accidentally dropped. The air passage, d , facilitates the discharge of the lubricant from the absorbent material.

What I claim is,

1. In a pair of scissors or shears, the combination with the shear members, and their pivot, of a compressible lubricant saturated member confined wholly within one of said members only, to the rear of the pivot only, 70 and contiguous to the adjacent faces of the two members.

2. In a pair of scissors or shears, the combination with the shear members, and their pivot, of a compressible lubricant saturated 75 member confined wholly within one of said members only, to the rear of the pivot only, and contiguous to the adjacent faces of the two members, and means for facilitating the flow of the lubricant from said member. 80

3. In a pair of scissors or shears, the combination with the shear members and their pivotal connection, of an absorbent lubricant-saturated material on one of the shear members only and disposed to the rear of the pivot 85 only and adjacent the contacting surface of the other shear member.

4. In a pair of scissors or shears, the combination with the shear members and their pivotal connection, of a compressible fibrous 90 absorbent lubricant-saturated material no one of the shear members only and disposed to the rear of the pivot only and adjacent the contacting surface of the other shear member. 95

5. In a pair of scissors or shears, the combination with the shear members and their pivotal connection, of an absorbent lubricant-saturated material on one of the shear members only and disposed to the rear of the pivot 100 only and adjacent the contacting surface of the other shear member, the shear member in which the lubricant-saturated material is confined being provided with a contracted air passage to facilitate the discharge of the 105 lubricant.

6. In a pair of scissors or shears the combination with the shear members and their pivotal connection, of a lubricating material seated in one of the shear members adjacent 110 the contacting surface of the other shear member, the first shear member having an

air passage leading to the lubricating material said passage being of materially less dimension than the lubricating material.

7. In a pair of scissors or shears, the combination with the shear members and their pivot of compressible absorbent means to the rear of the pivot only and in one member only for oiling and cushioning the coöperating parts, the member containing said absorbent means having a restricted air passage leading therefrom to facilitate the discharge of the oil.

8. In a pair of scissors or shears the com-

bination with the shear members and their pivotal connection, of compressible lubricant-saturated material in one only of the shear members in the rear only of the pivotal connection contacting with the adjacent surface of the other shear member.

In testimony whereof I have affixed my signature in presence of two witnesses.

ERNEST HUNOLD.

Witnesses:

HORATIO E. BELLOW,
WALTER E. GOODWIN.

It is hereby certified that in Letters Patent No. 880,535, granted March 3, 1908, upon the application of Ernest Hunold, of Providence, Rhode Island, for an improvement in "Scissors and Shears," an error appears in the printed specification requiring correction, as follows: In line 91, page 1, the word "no" should read *on*; and that the said Letters Patent should be read with this correction therein that the same may conform to the record of the case in the Patent Office.

Signed and sealed this 24th day of March, A. D., 1908.

[SEAL.]

C. C. BILLINGS,
Acting Commissioner of Patents.
